COLLAPSIBLE TABLE LEG HINGE AND
LATCH STRUCTUREFloyd M. Overbey, Chicago, Ill., assignor to Ero
Manufacturing Company, Chicago, Ill., a cor-
poration of Illinois

Application June 26, 1944, Serial No. 542,184

1 Claim. (Cl. 311—99)

1

This invention relates to collapsible tables and, more particularly, to a combination hinge and manually controlled latch structure for pivotally or hingedly mounting the leg of a collapsible table at the underside of the table top and for latching the table leg in erected or upright position.

The primary object of the present invention is to provide a new and improved and relatively simple but efficient combination hinge and manually controlled latch structure for pivotally or hingedly mounting table legs at the underside of the top of a collapsible table top and in such a manner that the table leg will automatically become latched against collapsing movement when swung into upright or erected position but may readily be unlatched for movement into collapsed position by means of a manually operable latch.

Another object of the invention is to provide a novel construction and arrangement of the manually operable latch which is embodied in the new device and which renders the latch readily accessible and easily operated.

Other objects of the present invention will be apparent from the following description and claims and are illustrated in the accompanying drawings which, by way of illustration, show preferred embodiments and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claim.

Fig. 1 is a side elevational view of a collapsible table embodying the present invention;

Fig. 2 is a fragmentary bottom plan view of the table shown in Fig. 1 but showing the table legs in collapsed position;

Fig. 3 is a bottom plan view, partly in section, of the new combination table leg hinge and latch structure, showing the table leg latched in upright position;

Fig. 4 is a side elevational view, partly in section, showing the new combination table leg hinge and latch structure and showing the table leg latched in erected or upright position;

Fig. 5 is an enlarged side elevational view, partly in section, showing the new combination table leg hinge and latch structure and showing the table leg in collapsed or folded position; and

Fig. 6 is a fragmentary vertical sectional view of the new combination table leg hinge and latch

2

structure and showing the relationship of the parts embodied therein to the inner end portion of the table leg.

A collapsible table embodying the present invention is illustrated in Fig. 1 of the drawings, wherein it is generally indicated at 10, and said table may be a collapsible table of any type such, for example, as card tables and the like.

The collapsible table 10 embodies a top 11 and supporting frame or side wall 12 which may be of any suitable design, shape, and construction, and the table 10 also embodies legs 13 which are arranged at the corners thereof. The legs 13 are identical construction and are preferably hollow legs composed, at least in part, of tubular metal, that is to say, at least the upper end portions of the legs are hollow or tubular although, if desired, the lower portions may be made of solid material such, for example, as wood or the like.

20 The new combination table leg hinge and latch structure is generally indicated at 14 and while there would, of course, be four of them in a collapsible table, one for each leg 13, these devices are all identical in construction and hence only 25 one will be described herein.

20 The new combination table leg hinge and latch structure 14 comprises a U-shaped hinge member or metallic casting 15 which may be mounted upon the table 10 at the underside of the table top 11 in any suitable manner, as, for example, by means of a supporting bracket or casting 16 which has end portions or arms 17 attached to the table frame 12, this supporting bracket 16 having an offset intermediate portion 18 to which the end wall 19 of the U-shaped hinge member 15 may be attached (Fig. 3) in any suitable manner as, for example, by welding or the like.

25 The U-shaped hinge member 15 includes a pair of side or cam plates 20 and each of these cam plates 20 has an arcuate cam surface 21, a notch 22 being provided in each of the cam surfaces 21 adjacent the lower end thereof (Fig. 5), for a purpose which will be described presently.

30 The upper or inner end portion of the table leg 13 is shown as having a U-shaped hinge member or sleeve 23 attached thereto, in any suitable manner, as by welding 24, although this sleeve might be dispensed with, if desired, and the parts made all in one piece. This U-shaped sleeve 23 includes a pair of spaced parallel side walls 25 which are fitted closely against and are guided in their movement by the adjacent parallel cam and guide plates 20 of the member 15 between which the side walls 25 of the U-shaped sleeve 23 are arranged. However, as shown the sleeve

23 and the body of the table leg form a single unitary rigid table leg construction and the said table leg is pivotally or hingedly mounted at its upper or inner end by hingedly mounting the side walls 25 of the U-shaped sleeve 23 upon a hinge pin 26 which extends between the side or cam plates 20 of the U-shaped hinge member 15.

A manually operable slide plate or latch control member 27 is slidably mounted upon the upper or inner end portion of the table leg 13, at the open side of the U-shaped sleeve 23, that is to say, between the arms or side walls 25 of the sleeve 23, this slide plate or latch control bar 27 having a curved finger grip 28 at its outer or lower end. The slide plate 27-28 is attached, by a headed bolt 29, to the central portion of a slidable latch bar 30. The bolt 29 works in a slot 36 which is formed in the wall of the tubular leg 13 and the other end portions of this slidable latch bar 30 work and are guided in corresponding companion slots 31 one of which is formed in each of the side walls 25 of the U-shaped sleeve 23. The slidable latch bar 30 has outer end portions 32 (Fig. 3) which function as camming or latching end portions of the slidable latch bar 30 in that these outer end portions 32 of the latch bar 30 cam upon and ride over the arcuate cam surfaces 21 of the side or cam plates 20 of the U-shaped hinge member 15, the outer end portions 32 of the slidable latch bar 30 being urged into camming engagement with the arcuate cam surfaces 21 of the side or cam plates 20 of the U-shaped hinge member 15 by means of a coil spring 33 which is arranged in the tubular leg 13, the inner end portion of the spring 33 being attached, as at 34, to the bolt 29 and the outer end portion of the spring 33 being attached, as at 35, to the inner wall of the tubular leg 13 by being bent thereover, as shown in Figs. 4 and 6.

In the use and operation of the present invention the table leg 13-23 may normally be disposed in collapsed or folded position, as in Figs. 2 and 5, and when thus disposed the camming outer end portions 32 of the latch bar 30 are urged by the spring 33 into camming engagement with the arcuate cam surfaces 21 of the cam or side plates 20 of the U-shaped hinge member 15.

The table leg 13-23 may be manually moved into erected position, as in Figs. 4 and 6, by manually grasping the table leg 13-23 and pivoting the same upon its hinge pin 26. During this movement the camming outer end portions 32 of the latch bar 30 will ride the arcuate cam surfaces 21 of the cam plates 20 and as and when the table leg 13-23 reaches erected position the camming outer end portions 32 of the latch bar 30 are urged by the spring 33 into latching engagement in and with the notches 22 which are formed in the cam surfaces or cam tracks 21 of the cam plates 20 at the lower ends thereof (Fig. 5) thereby firmly latching the table leg 13-23 in fully erected position. During this operation the camming outer end portions 32 of the latch bar 30 work in the slots 31 which are formed in the side walls 25 of the U-shaped sleeve 23 and the bolt 29 works in the slot 36.

However, when it is desired to fold or collapse the table legs 13 this may readily be accomplished by manually grasping the finger grip 28 on the latch operating bar 27 and pulling outwardly against the action of the spring 33, so as to retract the camming and latching outer end portions 32 of the latch bar 30 from the notches 22, the latch control bar 27-28 being held against the action of the spring 33 while the leg 13-23

is pivoted slightly in its hinge 26 so as to enable the camming and latching end portions 32 of the latch bar 30 to ride back into the cam tracks 21. During this operation the camming and latching end portions 32 of the latch bar 30 will again slide in the slots 31 and the bolt 29 will slide into the slot 36. The table leg 13-23 may then be pivoted into fully collapsed or folded position and during this operation the camming and latching end portions 32 of the latch bar 30 will ride over the arcuate cam surfaces or cam tracks 21, as the table leg 13-23 is pivoted upon its hinge 26 back into completely folded or collapsed position. It will be noted in this connection that during movement thereof the table leg 13-23 is guided by the side plates 20 of the member 15.

It will thus be seen from the foregoing description, considered in conjunction with the accompanying drawings, that the present invention provides a novel and simple but efficient combination hinge and latch structure for the legs of collapsible tables and thus accomplishes its intended object and has the desirable advantages and characteristics including those hereinbefore pointed out and others which are inherent in the invention.

I claim:

In a device of the character described, a substantially U-shaped rigid hinge member having an end wall and spaced integral similarly shaped and sized side-walls fixedly secured to the under side of a table top adjacent a corner thereof, the said side walls being arranged in spaced parallel vertical planes and having arcuately shaped edges with notches therein which open into the arcuate edges thereof, a table leg polygonal in cross-section at its hollow upper end, another substantially U-shaped movable hinge member having an end wall and integral similarly shaped and sized side-walls fixedly secured to and having a portion thereof extending beyond the upper end of the table leg with portions of its side-walls and the said end wall engaging certain of the polygonal portions of the upper portion of the table leg and having similar portions of the side-walls thereof each having a slot therein, and which last mentioned side walls project beyond another polygonal upper portion of the table leg oppositely of the portion engaged by the end wall of the movable hinge member thus providing a space between the said similar projecting portions of the side walls of the movable hinge member adjacent the upper end of the table leg, the movable hinge member being disposed in the space between the side-walls of the fixed hinge member with each hinge member having registered openings in their side walls, a pintle pin positioned in the said registered openings in and forming a pivot for the table leg, a substantially flat rectangularly shaped latch member positioned in the space between the projecting portions of the side-walls of the movable hinge member and contacting and slidably on the polygonal face of the table leg and having its ends extending through the slots in the movable hinge member and projecting beyond the sides of the table leg in engagement with the arcuate edges of the fixed hinge member, an elongated latch operating member having an offset end portion thereof overlying and contacting the latch member in the space between the projecting portions of the side-walls of the movable hinge member and an intermediate portion thereof slidably engaging the polygonal face of the table leg and with its other end extending outwardly from the

table leg to form a finger piece, the last mentioned polygonal face of the table leg having an elongated slot therein, the latch and latch operating members each having a registered opening which are in registry with the elongated slot, a bolt extending through the said openings and maintaining the latch and operating means therefor in proper association and having one end projecting through the last mentioned slot and into the hollow table leg, a coil spring within the upper hollow end of the table leg with one end thereof secured to the projecting end of the bolt and with its other end secured to the upper end edge portion of the table leg thus tensioning the latch and its operating member which are 15 slidable in a single plane only parallel with the polygonal face of the upper end of the table leg, whereby the projecting ends of the latch ride on the arcuate edges of the fixed hinge member when the table leg is moved on its pintle and the latch enters the opposite slots in the fixed hinge member to thereby temporarily fix the two hinge 20

members and the table leg together in extended position and by manually sliding the operating member and latch in a single plane to remove the latch from the said slots for moving the table leg to a folded position.

5 FLOYD M. OVERBEY.
